UNITED STATES PATENT OFFICE.

JOHN SISSON GRAHAM, OF THE UNITED STATES NAVY.

STEERING APPARATUS FOR VESSELS.

1,295,732.

Specification of Letters Patent.

Patented Feb. 25, 1919.

Application filed April 10, 1918. Serial No. 227,709.

To all whom it may concern:

Be it known that I, JOHN S. GRAHAM, United States Navy, a citizen of the United States, stationed on board U. S. S. *Vicksburg*, have invented certain new and useful Improvements in Steering Apparatus for Vessels; and I do hereby declare the following to be a full, clear, and exact description of the invention, such as will enable others skilled in the art to which it appertains to make and use the same.

My invention relates to improvements in steering apparatus for marine vessels, and it is intended more particularly to provide instead of the ordinary vertically-disposed steering rudder now generally used for such purposes a pair of independently operable rudders located on opposite sides of the vessel, preferably near the stern, and so arranged that either or both of the rudders may be swung from the inert to the operative position, or vice versa and in which the bearings for the rudder are located within the interior of the vessel so that they may be at all times readily accessible for purposes of lubrication, inspection, or repair.

My invention will be more fully understood after reference to the accompanying drawings, in which:

Figure 1 is a diagram showing one side of the stern of a vessel with the rudder on that side shown in full lines in the inert position, and in dotted lines in the full-rudder position.

Fig. 2 shows a similar diagram showing a section along the line 2—2 of Fig. 1, but showing both rudders in full lines in the inert position, and one of the rudders in dotted lines in the full rudder position.

Fig. 3 shows a section along the broken line 3—3 of Fig. 2, and looking in the direction of the arrows.

Fig. 4 shows a section along the line 4—4 of Fig. 3, and looking in the direction of the arrows.

Fig. 5 is a detail showing a perspective of one of the rudders partly broken away; and

Fig. 6 shows a modification in which the rudder is swung from the lower to the raised position instead of from the raised to the lower position, as indicated in Figs. 1 to 4.

A represents the hull of a vessel, and B represents a propeller mounted on the pro-

peller shaft C. As my invention has nothing to do with propelling mechanism, I have shown the propeller in the simplest form, but one or more propellers may be used and they may be arranged in any desired or convenient way, since the location and operation of the propeller does not materially affect the functioning of the steering rudders.

The rudders D and D' have their blades d mounted at any suitable angle on the shaft d', the blades of the opposite rudders being reversely disposed as shown in Figs. 2 and 4. I have shown the rudder blades as made integral with the rudder shafts, but the blades may be rigidly attached thereto if desired.

The rudder shafts d' are journaled in suitable bearings E mounted inside of the vessel at a suitable distance below the water line. The bearings may be part of or secured to any suitable bed plate, such as F, whereby a strong and rigid support for said bearings is secured.

The rudder shafts d' may be turned in any convenient way, as by means of the worm segment G engaging the worm H on the shaft I, driven by the electric motor K. Each rudder should have its own independently operated mechanism for rotating the rudder shaft. Since it will only be necessary to turn the rudder shaft through an angle of 90° to throw the rudder from the inert position to the position for the full rudder, it will be desirable to provide cut-out mechanism for automatically cutting off the electric current when the worm sector G is turned from the position for throwing the rudder to the inert position to that for throwing the rudder to the full rudder position.

Fig. 2 shows a section along the line 2—2 of Fig. 1, but showing both rudders in full lines in the inert position, and one of the rudders in dotted lines in the full rudder position.

Fig. 3 shows a section along the broken line 3—3 of Fig. 2, and looking in the direction of the arrows.

Fig. 4 shows a section along the line 4—4 of Fig. 3, and looking in the direction of the arrows.

Fig. 5 is a detail showing a perspective of one of the rudders partly broken away; and

Fig. 6 shows a modification in which the rudder is swung from the lower to the raised position instead of from the raised to the lower position, as indicated in Figs. 1 to 4.

A represents the hull of a vessel, and B represents a propeller mounted on the pro-

This electric circuit may be connected to the ship's dynamos and any suitable electric cut-out may be used.

The operation of the device is as follows:

Referring first to Figs. 1 to 4, in which the rudder when in the inert position is raised with its longitudinal axis in the vertical plane, and when in the full rudder position has its longitudinal axis in the horizontal plane, it will be seen that when in the raised position the pressure of the water

will act on the edge of the rudder and very little turning effect will be produced; while if the rudder be swung to the full rudder position, shown in dotted lines in Figs. 1 and 5 2, the front surface of the blade will engage the water with the result that there will be considerable turning effect.

To use what is known as a "smaller" helm the rudder may be turned to some intermediate position; the "fineness" of the helm depending upon the nearness with which the rudder approaches the inert position shown in full lines in Figs. 1 and 2.

If desired, both rudders may be thrown 15 to the full rudder, or any other operative position, in which case the two would serve as more or less of a brake, tending to retard the speed of the vessel and will be of assistance in stopping the vessel in a shorter 20 length than would be practicable with the stern rudder now generally in use.

The rudders may be set at any desired angle to the rudder shaft, but it may be more convenient to make this angle 25 form as nearly as practicable to the sides of the ship so that the rudder may be as much as possible out of the way when in the inert position. Some clearness, however, will be desired since when the rudder 30 turns, its longitudinal axis follows the surface of a cone, while the portions at each side of such axis are also swung forward or away from the vessel side, according to the direction of movement.

35 To avoid as much as practicable the protrusion of the rudders when in the inert position, they are preferably located at that part of the stern of the vessel where the hull slopes forward and outward, as shown 40 in Fig. 2.

If the rudder shaft d' is arranged so that it could be rotated through 360° there would be two inert positions for the rudder, 180° apart, and two positions for full rudder, also 180° apart, and each 90° from the position for the inert rudder; but since the maximum is secured by rotation of 90° only, it would only be necessary to provide for the rotation of the rudder shaft d' 45 through 90° , as indicated in Figs. 1 and 2.

I prefer to have the rudder elevated when in the inert position because the weight of the rudder will tend to help the steering engine in moving the rudder to the operative 55 position; and to restore the rudder to the inert position the pressure of the water will tend to assist the steering engine to overcome the weight of the rudder. If, however, it be found more convenient 60 or desirable to arrange the apparatus so that the rudder shall be in the inert position when lowered, and in the operative position when raised, the parts may be arranged as shown in Fig. 6, in which the 65 rudder is shown in the lowered and inert

position in full lines, and in the position for full rudder in dotted lines.

While a single pair of rudders will ordinarily be sufficient for practical purposes, it will be evident that two or more pairs of 70 rudders may be used, there being one rudder of each pair on each side of the ship and these rudders may be each independently operated for steering or braking purposes, or they may be all used together for braking 75 purposes.

It will be seen that with the herein described rudders being located abreast the hull of the vessel instead of in rear thereof, they will not be so apt to be wrenching 80 from their bearings, or injured by heavy seas striking the vessel transversely. Thus the principal cause of injury to the steering mechanism of vessels will be in a large measure avoided. Furthermore the bearings 85 for the rudder shaft and the mechanism for operating the same will all be located inside of the vessel and can be readily inspected at any time and kept properly lubricated, or may be accessible for repairs 90 whenever the same become necessary.

It will also be evident that it will not require the same power to swing the rudder about its pivot, as is the case with the ordinary stern rudder of a ship. Furthermore, 95 as has already been referred to, the weight of the rudder may be caused to assist the engine to throw the rudder from the inert position to the operative position, while the pressure of the water will tend to assist the engine to restore the rudder to the initial or raised position. Again, the stern of the vessel will not be kicked laterally as occurs 100 at present when the rudder is put over sharply.

There should preferably be apparatus for controlling the rudders located on the bridge of the ship as well as the control for each motor or group of motors on each side of the ship. I do not claim any particular 110 invention in this electric control, for many well known apparatus might be used for this purpose, such, for instance, as the control system on a motorman's platform of a street car. It will be obvious also that 115 signaling apparatus should be provided to indicate on the bridge the position of the rudder or rudders, but electric signaling apparatus are well known and I do not claim such apparatus as a part of my present invention.

By the use of the herein described construction a cheaper and stronger steering apparatus is secured which is less apt to be injured by the force of the waves, and 125 in which the operative parts can be more conveniently overhauled, than with the steering mechanism now generally in use.

It will be obvious that various modifications might be made in the herein de- 130

scribed apparatus, and in the construction, combination and arrangement of parts which could be used without departing from the spirit of my invention, and I do not 5 mean to limit the invention to such details unless particularly pointed out in the claims.

Having thus described my invention what I claim and desire to secure by Letters Patent of the United States is:—

- 10 1. Steering apparatus for marine vessels, comprising a pair of shafts journaled in the hull of the vessel and projecting outward therefrom, a rudder blade securely mounted on each shaft at an angle thereto, rigid 15 bearings carried by the vessel for said shafts, and means for independently rotating each of said rudder shafts in said bearings, substantially as described.
- 20 2. Steering apparatus for marine vessels, comprising a pair of shafts journaled in the hull of the vessel and projecting outward therefrom, a rudder blade securely mounted on each shaft at an angle thereto, rigid 25 bearings carried by the vessel for said shafts, a pair of electric motors, and gearing driven by each motor for independently rotating the corresponding rudder shaft, substantially as described.
- 30 3. Steering apparatus for marine vessels, comprising a pair of shafts journaled in the hull of the vessel and projecting outward therefrom, a rudder blade securely mounted on each shaft, the blades on opposite shafts being outwardly inclined in reverse directions, rigid 35 bearings carried by the vessel for said shafts, and means for independently rotating each of said rudder shafts in said bearings, substantially as described.
- 40 4. Steering apparatus for marine vessels, comprising a pair of shafts journaled in the hull of the vessel and projecting outward therefrom, a rudder blade securely mounted on each shaft, the blades on opposite shafts being outwardly inclined in reverse directions, rigid 45 bearings carried by the vessel for said shafts, a pair of electric motors, and gearing driven by each motor for independently rotating the corresponding rudder shaft, substantially as described.
- 50 5. Steering apparatus for marine vessels, comprising a pair of shafts journaled in the hull of the vessel and projecting outward therefrom, a rudder blade securely mounted on each shaft at an angle thereto, rigid 55 bearings carried by the vessel for said shafts, a pair of electric motors, and gear-

ing driven by each motor for independently rotating the corresponding rudder shaft with an automatic cut-out controlled by the rotation of each rudder shaft for cutting off 60 the electric current when said rudder shaft has been turned through a predetermined angle, substantially as described.

6. Steering apparatus for marine vessels, comprising a pair of shafts journaled in 65 the hull of the vessel and projecting outward therefrom, a rudder blade securely mounted on each shaft, the blades on opposite shafts being outwardly inclined in reverse directions, rigid bearings carried by 70 the vessel for said shafts, a pair of electric motors, and gearing driven by each motor for independently rotating the corresponding rudder shaft, with an automatic cut-out controlled by the rotation of each rudder 75 shaft for cutting off the electric current when said rudder shaft has been turned through a predetermined angle, substantially as described.

7. Steering apparatus for marine vessels, comprising a plurality of oppositely disposed shafts journaled in the hull of the vessel and projecting outward therefrom, a rudder blade securely mounted on each shaft at an angle thereto, rigid 80 bearings carried by the vessel for said shafts, and means for independently rotating each of said rudder shafts in said bearings, substantially as described.

8. Steering apparatus for marine vessels, comprising a plurality of oppositely disposed shafts journaled in the hull of the vessel and projecting outward therefrom, a rudder blade securely mounted on each shaft at an angle thereto, rigid 85 bearings carried by the vessel for said shafts, a pair of electric motors, and gearing driven by each motor for independently rotating the corresponding rudder shaft, substantially as described.

9. Steering apparatus for marine vessels, comprising a pair of shafts journaled in the hull of the vessel and having their axes in a vertical plane transverse to the longitudinal axis of the vessel, a rudder blade securely 105 mounted on each shaft at an angle thereto, rigid bearings carried by the vessel for said shaft, and means for independently rotating each of said rudder shafts in said bearings, substantially as described.

In testimony whereof I affix my signature.
JOHN SISSON GRAHAM.
